UNITED STATES PATENT OFFICE

THOMAS T. GRAY, OF ELIZABETH, NEW JERSEY, ASSIGNOR TO THE GRAY PROCESSES CORPORATION, OF NEWARK, NEW JERSEY, A CORPORATION OF DELAWARE

PROCESS OF TREATING CRACKED HYDROCARBONS

Application filed January 10, 1927. Serial No. 160,065.

This invention relates to a process of treating cracked hydrocarbons and more especially to a method of hydrogenating the unsaturated hydrocarbons present in cracked distillates.

In my United States Patent No. 1,340,889 of May 25, 1920, I disclose a process of treating cracked distillate containing unsaturated hydrocarbons which comprises passing the distillate in vapor form through a catalytic agent such as fuller's earth to convert the unsaturated constituents by polymerization into compounds of higher boiling point which may be separated from the vaporized saturated hydrocarbons.

According to the present invention, advantage is taken of the fact that in the cracking of petroleum oils free hydrogen is produced. The desired portion of the distillate of the cracking operation which includes unsaturated hydrocarbons and free hydrogen is brought into contact with a catalytic material such, for example, as fuller's earth coated or impregnated with a metallic hydrogenation catalyst, preferably nickel, or a mixture thereof with fuller's earth and the like preferably at a temperature of approximately 200° C. if gasoline is being produced. I have found that, at this temperature, when the mixed vapors are brought into contact with the catalytic agent, the hydrogen gas very readily combines with unsaturated hydrocarbon compounds to produce saturated hydrocarbons. It may be that the hydrogen content is insufficient to saturate all the unsaturated hydrocarbons present and under these circumstances some of the unsaturated hydrocarbons which are not hydrogenated may be polymerized by contact with the fuller's earth into compounds having higher boiling points than the temperature at which the hydrogenation operation is carried on. The saturated hydrocarbons pass off as vapors and are subsequently condensed. The polymers condensed in the catalyst are collected and refluxed to the still for redistillation. This method of treating cracked distillate produces a higher yield of the desired product than heretofore, as the hydrogenation reduces materially the vol-

ume of the unsaturated hydrocarbons converted into polymers and increases the volume of the saturated hydrocarbon compounds discharged from the catalyst.

Other objects, novel features and advantages of the invention will be apparent from the following specification and accompanying drawing wherein the single figure illustrates diagrammatically an apparatus for treating hydrocarbons in accordance with the invention.

In the apparatus, 10 designates a cracking still which may be of any desired type. 11 is a fractionating device of any suitable type to which distillate in vapor form is led from the still by means of the pipe 12. A pipe 13 is provided for refluxing from the fractionator 11 to the still 10 any condensate collecting in the fractionator. 14 is a treating tower to which vapor from the fractionator is supplied through the pipe 15 controlled by the valve 16. A perforated funnel-like shelf 17 is arranged within the tower 14 and terminates in a discharge spout 18 extending through the bottom of the tower 14 and controlled by the valve 19. A pipe 20 leads from the treating tower 14 to a condenser 21 from which a pipe 22 leads to a storage tank 23. A reflux pipe 24 leads from the bottom of the treating tower 14 through a valve 25 and trap 26 to the inlet of a pump 27, the outlet of which communicates with the bottom of the fractionator 11. This provides means for returning to the still 10 for redistillation any condensate collecting in the bottom of the tower 14.

Within the tower 14 is provided a supply 28 of a catalytic material, such, for example, as fuller's earth, coated or impregnated with a metallic hydrogenation catalyst, preferably nickel, or a mixture thereof with fuller's earth. This material is prevented from sifting through the perforations in the shelf 17 by layers of mineral wool, screens, etc., arranged upon the shelf. Fluids, however, may pass through the treating material and the perforations in the shelf. Oil to be cracked is charged into the still 10 and heated in any suitable manner and is vaporized under cracking temperature and pressure. The

distillate, which comprises free hydrogen and unsaturated hydrocarbons along with saturated hydrocarbons, is supplied to the fractionator 11. After fractionation, the vapors 5 are passed through the catalytic material in the tower 14, preferably at a temperature of between 150° to 225° C. when gasoline is being produced. At this temperature, the hydrogen in the presence of the catalytic material 10 combines with unsaturated hydrocarbons to form saturated hydrocarbons which pass out through the pipe 20 in vapor form, along with the other saturated hydrocarbons. The free hydrogen may be sufficient to hydrogenate 15 all the unsaturated hydrocarbon compounds, but may be insufficient. Part of the unsaturated hydrocarbons which are not hydrogenated because of insufficiency of the hydrogen content may be polymerized by the 20 fuller's earth into compounds of higher boiling point and are condensed in the fuller's earth. These polymers trickle through the perforations and are collected in the bottom of the tower and refluxed to the still 25 for redistillation.

It is understood, of course, that if the process is carried on under super atmospheric pressure, which might be the case if the process is used in conjunction with a 30 cracking system of the type in which the distillate is condensed under pressure, the temperatures may run higher to an extent depending upon the pressure.

A higher yield of the desired product than 35 heretofore obtainable is obtainable by this process without additional cost except for the cost of metallizing the fuller's earth. The hydrogen produced by the cracking operation, and which formerly has been vented 40 as an uncondensable gas, is utilized to convert into saturated hydrocarbon compounds a portion or all of the unsaturated hydrocarbon compounds which formerly were polymerized and refluxed for distillation. 45 The volume of polymers refluxed is substantially decreased and the volume of saturated hydrocarbon compounds discharged from the catalyst in vapor form is correspondingly increased.

50 I claim:

1. The process which comprises cracking petroleum oil and subsequently subjecting the cracked product at approximately 200° C. and in vapor form undiluted by extraneous 55 gases and mixed with free hydrogen produced solely in the cracking operation, to the action of fuller's earth impregnated with a metallic hydrogenation catalyst.

60 2. The process which comprises cracking petroleum oil and subsequently subjecting the cracked product at approximately 200° C. and in vapor form undiluted by extraneous 65 gases and mixed with free hydrogen produced solely in the cracking operation, to the ac-

tion of fuller's earth coated with a metallic hydrogen catalyst.

3. The process of producing gasoline which comprises cracking petroleum oil, fractionating the cracked product to separate the gasoline content and subsequently subjecting the cracked gasoline at approximately 200° C. and in vapor form undiluted by extraneous gases and mixed with free hydrogen produced solely in the cracking operation, to the action of a mixture of fuller's earth and fuller's earth coated with a metallic hydrogen catalyst, thereby hydrogenating the unsaturated hydrocarbons present to an extent depending upon the hydrogen content and polymerizing a part at least of the remaining hydrocarbons. 75

4. The process which comprises cracking petroleum oil and subsequently subjecting the cracked product at approximately 200° C. 85 and in vapor form undiluted by extraneous gases and mixed with free hydrogen produced solely in the cracking operation, to the action of fuller's earth coated with nickel.

5. The process of producing gasoline which 90 comprises cracking petroleum oil and subsequently subjecting the cracked gasoline at approximately 200° C. and in vapor form undiluted by extraneous gases and mixed with free hydrogen produced solely in the cracking operation, to the action of a mixture of fuller's earth and fuller's earth coated with nickel to hydrogenate the unsaturated hydrocarbons to an extent depending upon the 95 hydrogen content and to polymerize part at least of the remaining unsaturated hydrocarbons.

6. The process of producing gasoline which 100 comprises cracking petroleum oil, fractionating the cracked product to separate gasoline from the remainder and subsequently subjecting the cracked gasoline at approximately 200° C. and in vapor form undiluted by extraneous gases and mixed with free hydrogen produced solely in the cracking operation, to the 105 action of fuller's earth coated with a metallic hydrogenation catalyst. 110

In testimony whereof, I have signed my name to this specification.

THOMAS T. GRAY.
